UNITED STATES PATENT OFFICE.

HARPER F. SMITH, OF PHILADELPHIA, PENNSYLVANIA, ASSIGNOR TO
GRACE A. SMITH, OF SAME PLACE.

VAPOR-BURNER.

SPECIFICATION forming part of Letters Patent No. 651,211, dated June 5, 1900.

Application filed September 16, 1899. Serial No. 730,680. (No model.)

To all whom it may concern:

Be it known that I, HARPER F. SMITH, a citizen of the United States, residing in the city and county of Philadelphia, State of Pennsylvania, have invented a new and useful Improvement in Vapor-Burners, which improvement is fully set forth in the following specification and accompanying drawings.

10 My invention relates to burners in which gasolene or other hydrocarbon in a vaporized condition is employed as the lighting medium; and it consists of novel means for more effectively vaporizing the same than heretofore.

15 It also consists of a novel construction of valve, valve-casing, and means for enabling the oil to be fed to and through said valve in a regular and uniform manner to the burner.

20 It also consists in the employment of a supply-reservoir having a pipe leading therefrom to a chamber filled with wicking or similar material, whereby back vapor-pressure into said reservoir is prevented, said chamber

25 leading into a pocket in the valve-casing, which latter is rigidly secured in position upon the lantern by novel means, whereby oscillation or vibration of the valve or burner, which is connected thereto by a suitable

30 pipe, is prevented, thus affording protection against the breakage of the mantle, since said valve, burner, and mantle are immovably supported relative to each other.

It also consists of a novel construction of 35 improved superheating and commingling devices for the air and vapor contained within the burner and to be hereinafter referred to, whereby the flame is caused to strike the entire inner surface of the mantle, thereby producing an intense, steady, and brilliant incandescent light at all times.

It further consists of novel details of construction, all as will be hereinafter fully set forth, and particularly pointed out in the 40 claims.

Figure 1 represents a side elevation of a burner embodying my invention, the generator, controlling-valve, and devices for cleaning the hydrocarbon and preventing back pressure, as well as the means for supporting the valve, being shown in section. Fig. 2

represents a plan view of the burner seen in Fig. 1 with the mantle removed. Fig. 3 represents a section on line *x* *x*, Fig. 2. Fig. 4 represents a perspective view of the burner-cone removed. Fig. 5 represents a detached perspective view of an inner cap. (Seen also in Fig. 3.) Fig. 6 represents a detached perspective view of a supporting-frame for the cap. (Seen also in Fig. 3.) Fig. 7 represents a sectional view of a controlling-valve and the devices for cleaning the hydrocarbon and adjuncts. (Seen also in Fig. 1.) Fig. 8 represents a sectional view of the valve-casing with the receiver for dirt, water, &c., omitted. Fig. 9 represents a side elevation of a burner embodying my invention, in which I employ a chimney and its adjuncts, whereby the mantle is protected. Fig. 10 represents a section on line *y* *y*, Fig. 9. Fig. 11 represents a perspective view of the chimney-support seen in Fig. 10. Fig. 12 represents a perspective view of the inner cap seen in Fig. 10. Fig. 13 represents a modified form of Fig. 12. Fig. 14 represents a detached perspective view of the perforated cap seen in Fig. 9 and 10. Fig. 15 represents a perspective view of a spider in detached position. Figs. 16 represents a sectional view of a tube lined with asbestos.

Similar numerals of reference indicate corresponding parts in the figures.

Referring to the drawings, 1 designates a reservoir for the reception of the gasolene or other hydrocarbon and having the pipe 2 leading therefrom to the chamber 3, which preferably consists of the shell 4, having the cap 5 secured thereto and provided with the nipple 6, which engages said pipe 2. The chamber 3 is filled with wicking or other packing material 7, which acts as an absorbent and is packed sufficiently tight, so as to permit the proper flow of the gasolene, which, with the pressure of the oil from above by reason of the gravity of the column of said oil, I have found by experiment forms a sufficient resistance to any vapor back pressure and gives an increased pressure in the conduit to the burner. It will be apparent from the foregoing that I utilize the gravity-pressure of the oil, as the column of the latter flowing through the tightly-packed wicking 7 forms a barrier to the back

pressure of the vapor which is contained in the tube leading to the burner, whereby an exceedingly steady and uniform light is produced.

5 designates a nipple depending from the base of the chamber 3 and discharging into the pocket 9 of the valve-casing 10, said pocket serving to hold sufficient liquid, so that the additional pressure may be uniform 10 and regular.

11 designates a port leading from the lower portion of the pocket 9 and controlled by the valve 12, which is mounted in the boss or extension 13 of the valve-casing, which extends 15 through a rib 14 of the lamp or lantern frame and is held in position by the nut or washer 15 or other suitable clamping device.

16 designates a passage leading from the port 11 to the drip-chamber or trap 17, which 20 acts as a receiver for all dirt, water, or other objectionable matter, the lower end of said chamber having a closure 18, which latter, as well as said chamber, may be continued to and through an opening in the bottom of the 25 lantern, if desired. At the upper end of closure is a slit 52, sufficient to permit the running out of any objectionable matter without removing closure from drip-chamber, and it will also be apparent that the chamber 3 may be located exteriorly of the lantern, as shown dotted in Fig. 7, or it may be located at outlet-chamber of valve, in which case the supply-pipe from reservoir would connect with valve and the valve outlet-chamber 35 would connect with the upper screw-cap of chamber 3, and the supply-pipe leading into burner would connect with the lower screw-cap of said chamber. If the chamber 3 is located within the lantern, a covering of asbestos or similar material may be applied thereto, or said chamber may be constructed of some non-conducting material, so that the 40 gasolene may not be affected by the heat within the lantern. If desired, the drip chamber 45 or trap 17 may be omitted, as seen in Fig. 8, the valve-casing 10 seen therein being, however, rigidly secured, so that no displacement will occur during the manipulation of the valve 12.

50 19 designates a pack-tube in which asbestos or other similar indestructible material 20 is used, one end of said tube being continued into the valve-casing 10 for some distance, as will be understood from Figs. 1 and 7, while 55 the other end thereof is extended for some distance into the member 21 of the generator 22, the object of this being to extend over the end of the pack-tube adjacent to the burner an auxiliary heater which serves as a sheath, 60 thereby confining the heat and intensifying the vaporization, which expands the hydrocarbon to its full development before reaching the vapor-chamber, the opening 23 in the gas-chamber 24 permitting flame to play 65 against said sheath and also against the depending member 25 of said generator. In practice the portion 21 is threaded only near

the downward passage, and the casting is bored out from the threads to the entrance or outer end of said casting, where the pack-tube is primarily inserted. In Figs. 9 and 10 70 the pack-tube is simply secured directly into the member 21, leading into the downward passage 25, and the flame from the opening 23 plays directly against the supply-pipe. 75

In its expanded state the vapor passes down through the pipe 25 and up through the valved port 26, at which point it takes up a large percentage of the atmosphere, with which it commingles, thereby cooling the vapor and causing a contraction of the fixed gas. After this high percentage of atmosphere has been mixed with the vapor it passes up into the mixing tube or opening 27, which forms the entrance to the mixing-chamber 28, in which 80 the gas is again heated in its partially-mixed state, said gas next impinging against the top 29 of the cap 30 and rebounding and becoming heated and passing through the slots or openings 31 in said cap, where the molecules of air and gas again become thoroughly mixed, and after continuing up in the chamber 24 to the upper superheating-chamber 32 the gas after being thoroughly heated and commingled passes through the cone 33, which 90 rests upon or is fastened to the burner in any suitable manner. If desired, a perforated disk 34, such as seen in Figs. 9, 10, and 14, may be employed, and it will be understood that the cone or disk may be of any suitable corrosive 95 or non-corrosive material having either a perforated, slotted, or any other kind of outlet-opening to permit the egress of the gas. The cone shape causes a radiation of the heat in its entire inner surface, thereby causing an 100 extra superheating of the gas before leaving said cone, thereby giving it additional force and vitality as it fills the inner surface of the mantle. Besides it conveys in a radiant form 105 the heat down into the heating-chamber, which keeps the same in a highly-heated state, and it will be further apparent that the gas passing from the cone by its conformity to the shape of the mantle causes the 110 flame to strike the entire inner surface of the mantle, thereby producing an intense, steady, and brilliant incandescent light. The mantle at all times, owing to the gas exudations, is filled to its utmost capacity, and consequently the light is always regular and full. 115

When the flat surface or disk form is used, the discharge area is limited on account of the width of the mantle, and by increasing this area or surface, as shown in the conical form, I consequently increase the burning-surface of the burner and cause less resistance to the gas as it comes to the cone in its superheated state, which admits a larger percentage of air into the mixing and heating chamber than could be admitted by any flat 120 or disk form. Additional efficiency is obtained from the employment of the cone, since the hydrocarbon in the pack-tube, as seen in Fig. 1, is vaporized by the direct action of the 125

flame of the cone playing directly against that portion connected with the sheathing-tube. The cap 30 is supported upon the ring or frame 36 or its equivalent, which may have the depending legs 37, which rest on the plate 38, as seen in Fig. 3, or, if desired, said ring 36 can be supported directly on the contiguous plate 39, as seen in Fig. 10.

In connection with the disk 34 (seen in Figs. 9 and 10) I also employ an inverted cone 40, suitably supported, as by the connection 41, which leads to the center of said disk, so that a small space intervenes between said disk and cone, so that the gas rushing upon the pointed vertex of the cone is thrown to the topmost side of the burner and issues from the top of the disk 34 in its full force from the points nearest to the mantle, and consequently the burning gas centers higher and fills the mantle better than if the inverted cone were not employed. In conjunction with the disk 34 and the cone 40 I also prefer to employ the form of cap seen in Figs. 10 and 12, wherein I provide the portion 29 with the arms 42, which form a spider, wherefrom it will be seen that the slots 31 serve to throw the gas partly against the side of the burner and also upwardly through said spider.

When I employ the cap 43 seen in Fig. 13 in place of the cap seen in Fig. 12, it will be seen that the gas will be thrown directly through the slot 44 against the side of the burner, whence it passes up through the spider above it. The spider 45 (seen in Fig. 15) may be placed on the ring or frame 36, (seen in Figs. 3 and 6,) whereby it is held about in the middle of the burner, and thus serves to assist in the disintegrating and commingling of the air and gas and also keeps the same in an agitated condition, and thus produces a more brilliant light.

In the constructions seen in Figs. 9 and 10 I employ a chimney 46, which is held by the looped upright or rod 47, which is adjustable by means of the set-screw 48, the chimney seen in Fig. 9 being sustained on lugs 49, while in cases where it is desired to use a large chimney a perforated plate 50 is employed, as seen in Figs. 10 and 11, said plate having openings 51, through which the ends of said lugs pass.

It will of course be understood that other suitable devices may be employed for retaining the upper and lower portions of the chimneys in a stable and fixed position without departing from the spirit of my invention. It will also be apparent that the burner being supported solely by its connection to the pack-tube 20 and the latter being sustained from the valve-casing 10, which is rigidly secured in position, all undue jarring of the burner or mantle is prevented. It will thus be seen from the foregoing that the tube 27 constitutes a primary mixing tube or chamber, while the portion 28 constitutes a secondary mixing and heating chamber capped at the top, and the part 32 constitutes a tertiary mixing and

heating chamber, which discharges into the outlet cone or disk.

It is apparent in Fig. 16 that the pack-tube 19 may be lined with thin sheet-asbestos rolled in tubular shape and cut just to meet, simply that vapor may not come in direct contact with the heated metal, or a slight asbestos tube may be used.

I desire to call especial attention to my method of lining the tube with asbestos, since the asbestos is indestructible and tubes treated in this way last indefinitely.

Having thus described my invention, what I claim as new, and desire to secure by Letters Patent, is—

1. In a burner, a reservoir, a supply-pipe leading downwardly therefrom, a tube, suitably packed, in connection with said supply-pipe, a valve-casing suitably supported, a pocket in said valve-casing controlled by a valve, said valve and the part controlled thereby being located at one side of said pocket, and a trap in said valve-casing below said valve, said tube engaging said casing above said trap, in combination with a tube packed with asbestos and extending from said trap to a burner, and a generator having a sheath adjacent said burner, said tube being extended into said sheath.

2. The combination of a reservoir, a pipe leading therefrom to a chamber filled with packing, a valve-casing communicating therewith, a pocket in said casing controlled by a valve, a trap below said pocket, a pack-tube engaging said casing and continued into the latter above the base of said trap, said pack-tube being filled with asbestos or similar material, a burner and connections from said pack-tube to said burner.

3. The combination of a reservoir, a pipe leading downwardly therefrom, a chamber containing packing interposed in said pipe, a valve-casing connected with said chamber, a pocket in said casing controlled by a valve, a trap located below said pocket, a pack-tube engaged with said casing and having its end terminating above the bottom of said trap, asbestos in said pack-tube, connections from the latter to a burner, and an angular generator for said burner, a portion of said generator being prolonged forming a sheath, into which said pack-tube extends.

4. The combination of a lamp or lantern, a valve-casing engaging a portion of said lantern and having an extension projecting outside of said lantern, a clamping device on said extension, a valve engaging the latter, a pocket in said casing for the reception of hydrocarbon, a trap located below said pocket, an angular opening leading from said pocket to said trap and an angular outlet leading from said trap to the burner.

5. In a vapor-burner, a valve-casing, a pocket therein, a trap below said pocket and in alignment therewith, a valve controlling the communication between said pocket and

- trap, said valve being located at one side of said pocket, a pack-tube entering said casing at an angle to said trap and connections from said pack-tube to said burner.
- 5 6. The combination of a lantern, a valve-casing rigidly clamped to a portion thereof, a pocket in said casing, an angular opening leading downwardly from said pocket and controlled by a valve, a trap located below 10 said pocket and extending in substantial alinement therewith, and a pack-tube engaging said casing and having its end extended upwardly thereinto to a point above the base of said trap.
- 15 7. In a vapor-burner, the combination of a reservoir, a valve-casing, a pipe common thereto, a pocket in said casing, a trap below said pocket, an angular opening common to said trap and pocket, a valve controlling said opening, a pack-tube extended upwardly into said casing at an angle to said trap to a point above the bottom of the latter, said tube being packed throughout its entire length and a burner connected to said tube.
- 25 8. In a burner, a generator, a pack-tube extended into said generator and packed throughout its length, said generator being of angular shape and having a downwardly-extending portion leading to said burner, an 30 opening in the side of said burner adapted to permit flames to play upon said generator, a primary mixing tube or chamber, a secondary mixing or heating chamber, a cap closed at its top and open at its sides, and a tertiary 35 mixing and heating chamber having a perforated top, the latter being adapted to radiate heat against said generator.
9. In a burner, a mixing-tube, a secondary mixing-chamber above having apertured 40 sides, a tertiary mixing or heating chamber, an apertured cap above said tertiary chamber, a mantle located above said cap and surrounding the latter, an angular generator located adjacent said burner and a slot in the 45 latter adapted to permit flames to play upon said generator.
10. The combination of a burner, an angular-shaped generator located in proximity thereto, an opening in said burner for permitting the flames to play directly upon said generator, a perforated outlet-cap located in the upper portion of said burner, a primary mixing tube or chamber, a secondary mixing and heating chamber capped at its top and 55 open at its side and a tertiary heating and mixing chamber leading to said perforated cap, the latter permitting heat to be radiated upon said generator.
11. In a burner, a supply-pipe, a generator 60 heated by flames from an opening in the side of said burner, said generator having a downward passage leading to the burner, an air-mixing tube leading into a chamber above closed at its top and opened at its side, where- 65 by gas is thrown directly against the inner surface of the burner, a slotted distributor through which gas passes upwardly into the superheating-chamber and a perforated cap located in the upper portion of said burner.
12. A hydrocarbon incandescent burner 70 provided with a vaporizing-tube and a needle-valve discharging vapor into the mixing-tube of the superposed burner, the latter being divided into two compartments by means of a spider suitably supported therein, said spider being solid in the center and slotted in the outer portions thereof, in combination with a generator adjacent said burner and a slot in the latter for permitting flames to play upon said generator.
13. In a hydrocarbon incandescent burner, a plurality of mixing-chambers located therein, and an angular generator adjacent to said burner, a diagonal slot in the latter for permitting flames to play upon said generator, a perforated cap in the upper portion of said burner, supports extending laterally from the burner and a chimney surrounding the mantle and other supporting devices for sustaining a chimney of greater diameter.
14. The combination of a burner-tube, a burner, primary, secondary, and tertiary chambers therein, all of said chambers being constructed and located substantially as described, a perforated cap supported upon said burner-tube, a spider located in one of said chambers, supporting devices for said spider, a mantle having its lower edge surrounding said cap and means for supporting said mantle.
15. The combination of a burner, an angular generator adjacent thereto, a packing-tube extended into said generator for a portion of its length, a cone for said burner, a diagonal outlet from said burner adjacent to 105 said generator, said generator being located so that it is heated by flames discharged from said cone and also from an opening in said burner.
16. The combination of a lamp or lantern 110 frame, a reservoir, a valve-casing secured to said frame, a pipe common to the latter and to said reservoir, a chamber containing packing material located therein, an extension for said casing projecting through said lantern-frame, means for rigidly securing said extension to said frame, a valve located in said extension, a valved port leading downwardly from said pocket, a trap located below said pocket, and a connection from the upper portion of said trap to a burner.
17. The combination of a reservoir, a connection therefrom to a chamber filled with packing for preventing back pressure, a pocket below said chamber, and located in the 115 valve-casing, means for rigidly securing the latter to the lamp or lantern frame, a valved port located at one side of said pocket, a passage leading from said pocket to a trap, a burner, and a tube packed with asbestos or similar material leading from said valve-casing to said burner.
18. In a burner, a pack-tube filled with asbestos or suitable material, and leading to an

- angular generator, the latter being heated by the mantle and by flame through a diagonal slot in a side of the burner, the latter being adjacent to said generator, primary, secondary and tertiary heating and commingling chambers 27, 28 and 32 respectively, an outlet leading from said burner, a mantle, and means for causing the flame to be evenly discharged from said outlet upon said mantle.
19. The combination of a reservoir, a pipe leading downwardly therefrom, a chamber having a screw-cap projecting into said pipe, packing in said chamber, a valve-casing engaged thereby, means for securing said casing rigidly in position, a trap for said valve-chamber, and a pipe leading from the latter to the burner.
20. In a burner, a pack-tube, a lining of sheet or tube asbestos therefor whereby a large passage for the hydrocarbon is permitted, means for enabling said pack-tube to vaporize the hydrocarbon by heat impingement so greatly as to keep the passage-way so vapor-charged that the inlet to the vapor-chamber is so pressed and filled by expansion that an extra force or pressure is obtained as the vapor leaves said vapor-chamber at the needle-valve opening, a generator adjacent said burner and in engagement with said pack-tube, and an opening in said burner for permitting flame to discharge on said generator.
21. A burner having a mantle, a vapor-chamber, a mixing-tube, and gas heating and distributing chambers, in combination with a reservoir located above said burner, a valve, a tube intermediate said reservoir and valve, and an asbestos-lined tube connecting said valve with said vapor-chamber.
22. In a burner, a tube extending from a source of supply to said burner, in combination with an open asbestos chamber or tube extending longitudinally of and inside said metallic tube, the passage within said asbestos chamber or tube serving to evenly vaporize the hydrocarbon fluid and to convey the same in a highly-heated and expanded state to the vapor-chamber of the burner.
23. The combination of a burner, an angular generator adjacent one side thereof and a diagonal slot in said burner located in proximity to said generator, whereby flame is permitted to impinge directly upon the latter, for the reception of the end of a pack-tube, the latter being continued into said generator, which serves as a sheath and to inclose the discharge end of said pack-tube.
24. The combination of a burner, an angular generator adjacent thereto, a diagonal slot in said burner located in proximity to said generator, whereby flame is permitted to impinge directly upon the latter, and a pack-tube suitably packed and extending into said generator for some distance.
